UNITED STATES PATENT OFFICE.

FRANK MUNHOLLON, OF CLEVELAND, OHIO, ASSIGNOR OF ONE-THIRD TO CHARLES F. LOCKHART, OF CLEVELAND, OHIO.

KILN.

1,311,286.

Specification of Letters Patent. Patented July 29, 1919.

Application filed January 20, 1919. Serial No. 272,118.

To all whom it may concern:

Be it known that I, FRANK MUNHOLLON, a citizen of the United States, residing at Cleveland, in the county of Cuyahoga and 5 State of Ohio, have invented certain new and useful Improvements in Kilns, of which the following is a specification.

This invention relates to kilns, particularly adapted for burning or drying brick, 10 but capable of use on other articles if desired. The object of the invention is to provide improved means for distributing the heat in a kiln of the downdraft type, a characteristic feature of the structure being 15 the use of vertical flues arranged in the kiln, and adapted to conduct the gases from a lower compartment, below the floor, to an upper compartment, these compartments being separated by a floor on which the 20 bricks or other articles are supported, this floor having openings through which the gases pass downwardly, so that there is a continuous circulation downwardly through the floor and upwardly through the flues. 25 Means are provided for inducing the upward flow through the circulation flues.

In the accompanying drawings—

Figure 1 is a horizontal section of a kiln constructed according to the invention.

30 Fig. 2 is a section on the line 2—2 of Fig. 1.

In the drawings, the kiln is shown of the circular type, having an outer wall 6, a floor 7, and a closed crown 8. The floor 7 has 35 many passages through the same, and divides the chamber into upper and lower compartments, the former of which receives the material to be dried.

The fireplaces 9 are arranged at intervals 40 or spaced around the wall 6, and the number thereof will depend upon the size of the kiln or other conditions. I have shown four in the drawings, located at equal distances apart. A flue 9^a leads from each fireplace, 45 on the inner side of the wall 6, and conducts the gases to the upper part of the chamber, through which they flow downwardly, and thence through the openings in the floor 7 to the space under the floor, from which 50 space an outlet flue 11 leads to the stack 12. The mouth of this flue 11 is preferably located at the center of the kiln, and the flue has a damper 18.

The upper compartment is connected to 55 the lower compartment or space below the

floor by a plurality of uptake flues 10 which extend through the floor and are adapted to conduct gases from the space below the floor to the upper part of the drying chamber. These circulation flues are preferably located 60 in alternation with the flues 9^a and at equal distances apart, so as to cause a uniform distribution of heat. An updraft is induced in these circulation flues by means of jet nozzles 17, directed upwardly therein, and connected by pipes 16, which extend through the wall 6, to a pipe 14 extending around a kiln and to which air or steam may be supplied from a main 15. When compressed air or steam is discharged from the nozzles, 70 it creates an upflow therein, and by these means part of the gases which flowed downwardly through the floor into the space below are returned to the top of the kiln. Thereby a continuous circulation is provided, the hot gases passing through the 75 bricks or other material repeatedly, before they are drawn off to the stack, the central connection of the flue 11, at the lowest point of the kiln, taking only the colder gases 80 which settle in the bottom of the space below the floor. The invention is not limited to the particular form and arrangement of the parts shown, but various modifications may be made within the scope of the following 85 claims:

I claim:

1. A kiln comprising a chamber having a perforated floor with a space thereunder, a plurality of fireplaces spaced around the 90 chamber and discharging hot gases into the upper part thereof, an outlet from the space under the floor, and a plurality of circulating flues arranged around the chamber in alternation with the fireplaces and connecting 95 said space and the upper part of the chamber.

2. A kiln comprising a chamber having a perforated floor with a space thereunder, fireplace discharging hot gases into the upper part of the chamber, an outlet from the space under the floor, and circulation flues connecting said space and the upper part of the chamber and jet nozzles directed upwardly in said flues and adapted to induce 100 a circulation upwardly of gases from said space to the upper part of the chamber.

3. A kiln comprising a circular chamber having upper and lower compartments and a central outlet from the latter, a plurality 110

- of fireplaces arranged in the outer wall of the chamber and discharging into the upper compartment, a perforated floor between said compartments, a plurality of circulation flues arranged beside the outer wall in alternation with the fireplaces and connecting the lower to the upper compartment, and means to cause an updraft in said circulation flues.
- 10 4. A kiln comprising a chamber having upper and lower compartments, and a perforated floor between the same, means to supply hot gases to the upper compartment, an outlet from the lower compartment, cir-

culation flues connecting the upper and 15 lower compartments, and means to produce an updraft through said flues, to return gases from the lower to the upper compartment, said means comprising a fluid pressure pipe having jet nozzles directed up- 20 wardly in said flues.

In testimony whereof, I do affix my signature in presence of two witnesses.

FRANK MUNHOLLON.
